UNITED STATES PATENT OFFICE.

HIRAM A. BOND, OF WEST SPRINGFIELD, MASSACHUSETTS, ASSIGNOR, BY MESNE ASSIGNMENTS, TO THE NATIONAL LOOM AND WIRE COMPANY, INCORPORATED, OF SPRINGFIELD, MASSACHUSETTS, A CORPORATION OF CONNECTICUT.

LET-OFF AND TAKE-UP MECHANISM FOR LOOMS.

SPECIFICATION forming part of Letters Patent No. 727,533, dated May 5, 1903.

Application filed January 16, 1902. Serial No. 89,974. (No model.)

To all whom it may concern:

Be it known that I, HIRAM A. BOND, a citizen of the United States of America, and a resident of West Springfield, in the county of Hampden and State of Massachusetts, have invented certain new and useful Improvements in Let-Off and Take-Up Mechanism for Looms, of which the following is a full, clear, and exact description.

10 This invention is for improvement in looms, and more particularly looms for the weaving of wire-cloth, such as extensively used in Fourdrinier paper-machines and for other purposes.

15 The improvements specifically relate to the let-off and take-up mechanism.

An object of the invention is to provide a new and improved mechanism controlling both the let-off and take-up concurrently

20 which is very positive and reliable in its operation and which is susceptible by the substitution for one of the parts comprised therein of another part of slightly-changed size and character of varying the extent of let-off

25 and take-up, whereby to accord with the differences in the desired fineness or coarseness of the mesh of the wire-cloth to be woven in the loom.

Another object is to so form and combine 30 the actuating mechanism for the let-off and the take-up that the warp-beam or the take-up roller, or both, may be rotated either independently of each other and of the operating mechanism or both concurrently with 35 each other and still independently of and without obstruction by the operating mechanism therefor.

Another object is to provide that in the building up of the roll of cloth as made on 40 the take-up beam the increased size of the roll will not operate to strain the warps or interfere with the proper operation of the loom.

Another object of the invention is to generally improve, simplify, and cheapen the 45 construction of the loom and render the same capable of protracted use without liability of derangement.

To these ends the invention consists in the constructions and combination or arrange-

ment of parts or instrumentalities, all substantially as hereinafter described, in conjunction with the accompanying drawings and as covered in and by the claims.

In the drawings, Figure 1 is a side elevation of the loom equipped with the present improvements, a portion of the side frame being indicated as broken away for clearer illustration of some of the parts contributing to the novel mechanism. Fig. 2 is a plan view of the loom, an upper portion of the framing being understood as carried away on a plane which is just above the level of the warp and take-up beams. Fig. 3 is a longitudinal sectional view through the take-up beam, showing its slipping connection on the warp-beam shaft. Fig. 4 is an end view and partial section of the warp-beam.

Similar characters of reference indicate corresponding parts in all of the views.

In the drawings A represents the framing of the machine indicated as being of the same general design as commonly employed for wire looms.

B represents the warp-beam, having its arbor journaled horizontally in boxes *a a* at one end of the loom, and C is the take-up roll similarly horizontally mounted at the other end of the loom.

D is the main or driving shaft.

E represents the lay, pivotally mounted and suspended, having the reed at its lower portion.

E² represents the duplicated cam-lever, engaging the cams E³ in an ordinary manner, whereby the reciprocatory swinging motions are imparted to the said levers E² E² and from them through the connecting-bar *d* to the lay.

F F represent the harnesses, arranged for alternately rising and lowering motions as imparted to them by the levers F² F², intermediately pivotally mounted and actuated by the cam-rollers *e e* on the regularly-rotating and properly-speeded shaft A³ in the loom.

Both the extended end portions of the shafts or arbors of the warp-beam B and the take-up roll C have detachably affixed thereon by

the set-screws f the worm-wheels G and H, meshing in which are the worms g and h , which are carried, preferably detachably, at the opposite ends of the long shaft J, which 5 ranges nearly horizontally along the outer side of the machine-frame, one of the worms having its gearing engagement with the worm-wheel G beneath the latter, while the other has its engagement with the worm-wheel H above the latter, so that the rotation 10 of the shaft J will cause rotational movement of the let-off warp-beam and the take-up roll in the same direction as manifestly requisite.

15 There is comprised between the driving shaft A and the shaft J, having in common driving connection with both the warp-beam and the take-up roller, a medium of speed-reducing connection, which comprises there- 20 in means or provision whereby the degree of reduction of the speed and consequent extent of movement in each operation of the loom may be varied in percentage or proportion.

25 While the speed-reducing and variable connection may be somewhat modified from that here shown without departing from this invention, I will particularly describe the one shown.

The shaft A^3 by gearing is rotated from 30 driving-shaft A once in every two rotations of said driving-shaft. Suitably adjacent the said shaft A^3 is a short shaft k , parallel therewith, having removably mounted thereon a ratchet-wheel m , with which coacts a 35 pawl n , carried at the extremity of a pawl-carrying lever o , one end portion of which is hung for a swinging motion on the same shaft k as that on which the said ratchet-wheel is removably affixed. The swinging reciproca- 40 tory motion of the pawl-carrying lever o is imparted by the swinging lever l , which by a link l^2 is connected to the pawl-carrying lever o , and the reciprocatory motions of this lever l are imparted thereto in the one direction by 45 the adjustable cams l^3 , which are carried by the disk or rotary holder l^4 , and which cams im- pinging against the lever l^2 , one thereof at every half-rotation of shaft A^3 , which corresponds to a complete rotation of the main shaft and to 50 complete operations of the harnesses and lay. The spring l^5 retracts the lever l in pawl-carrier o . The adjustable cams l^3 are fitted in radial grooves in the disk l^4 , being secured with greater or less radial extension by means 55 of the bolt-and-slot connections indicated in Fig. 1. On the shaft k is a small spur gear-wheel 15, which meshes into the larger gear-wheel 16 on a shaft p , which is parallel with the one k , said shaft p having also there- 60 on a spur gear-wheel 17, which is smaller than the one 16 and in turn meshing into the larger spur gear-wheel 18 on the horizontal shaft q , which is parallel with shafts p and k . The said shaft q has on its end outside of the 65 frame the bevel-gear 19, of comparatively small diameter, which meshes with the larger bevel gear-wheel 20, affixed on the longitudi-

nally-extending worm-shaft J, having worm-gearing connection, as aforementioned, with the warp-beam and take-up roll. The said shafts k , p , and q have journal-bearings at their one end in the member r of a frame L, of a form to embrace three sides of a rectangle and which is bolted to the inner side of the said framing A of the machine, and the 75 gearing 15, 16, 17, and 18 is inclosed within this frame or rigid metal strap, and the other ends of the said shafts k , p , q are journaled in the adjacent portion of the side frame A. The motion primarily imparted to the main shaft 80 will, through the connections comprising the reducing-gearing, the ratchet-wheel, and the ratchet-wheel-actuating mechanism, impart a very slow rotational motion to the warp-beam and the take-up roll proportionately 85 more or less, according to the length of the teeth on the ratchet-wheel or the length of thrust of the pawl, and for establishing the conditions for let-off and take-up where the loom is being employed for a finer or a 90 coarser wire fabric the ratchet-wheel may be substituted by another having correspondingly finer or coarser teeth, and the actuating connections of the pawl-carrier will be correspondingly adjusted for the pawl to have its 95 proper throw to carry around the ratchet-wheel an extent equal to one of its teeth or a multiple thereof. By disconnecting the worm-gearing G, g or H, h either by removing or displacing the worms or the worm-wheels the 100 warp-beam and the take-up roll are left free for independent rotations to enable beaming on new warp-wires or the taking off of the finished fabric.

The take-up beam C, as shown in Fig. 3, is 105 mounted loosely on its shaft or arbor H^2 , and the beam has at one end a flanged or cup-shaped shell t , within the inner surface of which are arc-shaped friction-shoes u , having central radial perforations u^2 , and a collar v is affixed on the adjacent end portion of the take-up-beam shaft, the same having its radial studs v^2 extended for a sliding fit within the perforations of the friction-shoes. The said radial studs are screw-threaded, as 110 shown at v^3 , within their extremities, receiving thereon the nuts v^4 , which constitute adjustable stops or shoulders for the spiral springs w , which are between such stops and the shoes encircling the studs. By changing the position of the nuts the shoes may grip the beam to its shaft with a greater or less forcible degree of yielding engagement, and hence the diameter of the take-up beam and the woven cloth thereon becoming constantly variable 115 in the progress of the operation of the loom is compensated for by the yielding of the beam on its shaft when the predetermined maximum of strain on the warps shall have been reached.

Having thus described my invention, what I claim, and desire to secure by Letters Patent, is—

1. In a let-off and take-up mechanism for

looms, in combination, the warp-beam and the take-up beam having worm-wheels on their shafts, and a shaft extending from adjacent the shaft of the one to adjacent the shaft 5 of the other, and having worms gearing with said worm-wheels of said shafts, a driving-shaft and a secondary shaft having a ratchet-wheel thereon, a pawl-carrying arm pivotally hung having a pawl coacting with said ratchet-wheel, reducing-gearing connected with and between the ratchet-shaft and the worm-shaft, a rotary disk, primarily driven from the main shaft, having one or more radially-adjustable cams, a lever linked to the pawl-carrying arm, with which said cams engage, and means for retracting the lever.

2. In a let-off and take-up mechanism for looms, the combination with the warp-beam and the take-up beam, having worm-wheels 20 on their shafts, and a shaft extending from adjacent the shaft of the one beam to adjacent the shaft of the other, having worms in gear with the worm-wheels on the beam-shaft, and a driving-shaft, of a shaft *k* having a ratchet-wheel thereon, and a pinion-wheel 15, further shafts *p* and *q* having speed-reducing gearing and the latter one of the series having an extension adjacent the worm-shaft, and provided with a bevel gear-wheel 19 in mesh with 25 a gear-wheel 20, which is affixed to the worm-shaft, the pawl-carrier *o* and pawl *n* engaging

the ratchet-wheel, a shaft in driving connection with the main shaft having the disk *h* provided with the radially-adjustable cam and a lever *l* linked to the pawl-carrier, and 35 located to be impinged against by said cams, to be operated thereby and the retracting-spring *f*, substantially as described.

3. In a device of the character described, the combination of a take-up beam, a shaft 40 on which the beam is loosely mounted, the beam having a cup-shaped end, shoes arranged to rotate with the shaft, and springs arranged to press the shoes against the inner periphery of the cup-shaped end. 45

4. In a device of the character described, the combination of a take-up beam, a shaft on which the beam is loosely mounted, the beam having a cup-shaped end, a collar secured on said shaft and having radial studs, 50 nuts engaging said studs, friction-shoes having apertures engaging the said studs, and spiral springs encircling the studs and bearing on the nuts and the shoes, and arranged to force the shoes against the inner periphery 55 of the cup-shaped end.

Signed by me at Springfield, Massachusetts, this 11th day of January, 1902.

HIRAM A. BOND.
